UNITED STATES PATENT OFFICE.

CHARLES D. YOUNG, OF PITTSBURGH, PENNSYLVANIA.

TRANSFER MECHANISM.

1,160,355.

Specification of Letters Patent. Patented Nov. 16, 1915.

Application filed May 10, 1911. Serial No. 626,377.

To all whom it may concern:

Be it known that I, CHARLES D. YOUNG, a citizen of the United States, residing at Pittsburgh, in the county of Allegheny and 5 State of Pennsylvania, have invented certain new and useful Improvements in Transfer Mechanism, of which the following is a specification.

The invention relates to transfer mechanism and primarily to transfer mechanism for use in connection with an automatic stoker, for transferring the fuel from the tender of a locomotive to the locomotive fire-box. The invention has for its principal objects; the provision of an improved arrangement of feed chutes for supplying a plurality of underfeed stoker troughs in the locomotive fire-box; the provision of an improved form of increment feeding plunger 20 for supplying fuel from the tender to the transfer chutes; the provision of an improved door arrangement for controlling the supply of fuel from the tender to the transfer chutes; and the provision of a 25 simplified and improved arrangement of connections for securing the actuation of the various parts of the feed mechanism from a main cross-head. One embodiment of the invention is illustrated in the accompanying 30 drawings, wherein:—

Figure 1 is a longitudinal section through the apparatus as applied to a locomotive and tender, Fig. 2 is a diagrammatic plan view of the various operating connections, Fig. 3 is a partial plan view of the transfer mechanism on the tender and locomotive, the feed chutes being removed, but their position with respect to the mechanism shown being indicated by the dotted lines, Fig. 4 is a 40 plan view of the transfer chutes, Fig. 5 is a section on the line V—V of Fig. 4, Fig. 6 is a section on the line VI—VI of Fig. 4, Fig. 7 is a side elevation of the front end of the transfer chute, and Fig. 8 is a two part 45 section through the transfer mechanism, the left hand half being taken on the line VIII—VIII of Fig. 1, and the right hand half being taken on the line VIII'—VIII'.

This apparatus is designed to be used in 50 connection with stoker mechanism, such as that shown in my co-pending application, Serial No. 626,376, filed May 10, 1911, in which three underfeed troughs are provided, such troughs being fed by a main piston at 55 the front end of each trough, and by three auxiliary pistons arranged in series in each trough, the right hand end of the section

shown in Fig. 1 illustrating the arrangement of the auxiliary pistons in one of the three feed troughs.

Referring to the general arrangement of parts as shown in Figs. 1, 2 and 4; the parts may be enumerated as follows; 1 is the fire-box of the locomotive; 2 is one of the underfeed troughs in such fire-box, which troughs are provided with the auxiliary feed pistons 3; 4, 5 and 6 are the main feed pistons for supplying fuel to the front ends of the feed troughs, such feed pistons working in the cylinders 7, 8 and 9 (Fig. 3); 10 is a cross head directly connected to the three pistons 4, 5 and 6 and slidably guided and supported in the cylinders 7, 8 and 9; 11 and 12 are steam engines mounted upon the frame of the locomotive, and providing the power 60 for the actuation of the entire stoker and transfer mechanism; 13 is a transfer shaft provided with the cranks 14 and 15 connected to the pistons of the engines 11 and 12; 16 and 17 are rocker arms carried by the 65 shaft 13 and connected at their upper ends to the cross head by means of the connecting rods 18 and 19; 20 and 21 are connecting rods pivoted at their front ends to the cross head 10 and at their rear ends to the framework 22 which actuates the auxiliary pistons 3; 23 and 24 are feed chutes whose front ends are arranged to discharge to the 70 hoppers above the cylinders 7, 8 and 9 (Fig. 3), and whose rear ends lie below the discharge opening 24' in the bottom of the tender; 25 is a feed plate or plunger working transversely of the opening 24 for feeding the fuel rearwardly and crushing it; 26 (Fig. 3) is a transverse bar pivoted to the 75 rear end of the plate 25 and operated from the cross head 10 by means of the connecting rods 27 and 28; 29 is a door slidably mounted beneath the plate 25 and operable to control the supply of fuel by means of 80 the handle 30; 31 are feed fingers (Fig. 4) mounted for reciprocation in the feed chutes and adapted to give the fuel in such chutes a step-by-step movement, in a manner well known in the art; and 32 is a piston or plunger mounted to reciprocate in the chutes 85 and to give the fuel its preliminary forward movement therein.

The ends of the chutes 23 and 24 are so arranged as to discharge to the three hoppers 110 33, 34 and 35 as indicated in Figs. 3 and 4. This is accomplished by flaring the ends of the chutes and providing the deflecting members 36 and 37, so arranged that the

same amount of fuel is fed through the passage 38 as is fed through the passages 39 and 40. The deflectors 36 and 37 are pyramidal members built up of sheet-metal plates. As indicated in Fig. 4 the troughs 23 and 24 are spaced apart and held rigidly in their relative positions by means of the plates 41, 42 and 43, the troughs being otherwise open upon their tops. The reciprocation of the feed flaps 31 in the chutes is secured by means of the side bars 44 (Figs. 4 and 8), which side bars are mounted for longitudinal reciprocation, and carry transverse shafts 31', which in turn carry the flaps 31, the flaps being provided with ribs 45 upon their rear sides (Fig. 5), which ribs act as stop members as indicated in Fig. 7, taking against transverse bars 46 and preventing the flaps from moving farther to the rear than the position in Fig. 7. The rear ends of the reciprocatory bars 44 carry the piston 32, so that such piston reciprocates in unison with the feed members 31.

The reciprocation of the bars 44 is secured by means of the plate 47 (Fig. 4), which plate 47 extends clear across the two chutes and is securely riveted to each of the four bars 44. On the underside of the plate between the chutes is riveted a casting 48 provided with a fork 49, which fork 49 is engaged by the connecting rod 50 (Figs. 1 and 3). The connecting rod 50 has its other end pivoted to a lever 51 carried at its lower end in brackets 52' supported upon the frame 35 (Figs. 1 and 8), and at its upper end is provided with a fork in which is pivoted the end of the connecting rod 52, the other end of such connecting rod 52 being pivoted to the cross-head 10 as indicated in Figs. 1 and 2.

As indicated in Figs. 2, 3 and 8 the plate 25 which acts as a feeding and crushing piston or plunger is provided with two openings 53 and 54 separated by the partition 55, the said opening being adapted to register with the opening 24' when the plate is in its retracted position as indicated in Fig. 1. At this time the outlet from the tender to the chutes is entirely closed off by the front edge 56 (Fig. 1) of the plate 25. When the plate 25 moves to the left, the charge of coal in the two openings 53 and 54 is carried to the left, the larger chunks being crushed against the edge 57 of the opening 24', and this charge, being carried out past the edge of the door 29, is dropped into the hoppers 58 leading into the chutes (Fig. 5). The space between the two chutes lying within the hopper 58 is covered by means of the member 59 (Fig. 6). The plate 25 is also provided with a series of upright rods 60 (Figs. 2 and 3), constituting agitators for preventing any bridging of the coal above the opening 24'.

In order to regulate the supply of fuel

furnished by the apparatus without changing its speed or stroke, the door 29 is provided, which door is slidably mounted in the casting 61 in the manner indicated in Fig. 8. A transverse bar 62 is secured to the bottom of this door, and this transverse bar or rod has pivoted to each of its ends, a connecting rod 63 (Figs. 1 and 8), such connecting rods being pivoted at their other ends to the upright cranks 64. The lower ends of these cranks 64 are keyed to a transverse shaft 65 (Fig. 8), so that the two cranks may be rocked in unison, and one of these cranks has pivoted adjacent its upper end a connecting rod 66, the other end of which is connected to a bell crank lever 67. This bell crank lever is operated by the handle 30, which handle 30 is guided vertically and provided with the usual means for locking it in any desired position. By this means the door 29 may be shifted to any desired position, and the feed to the chutes regulated. With the door in the position shown in Fig. 1, a maximum feed is allowed, and this feed may be reduced by moving the door to the left. The door is supported at its front end by a transverse bar 68 over which the door slides. This arrangement of door beneath the plunger or plate 25 is advantageous over the old style arrangement with the door above the plate or plunger for several reasons. In the first place, there is no necessity of slotting the door to receive the agitators 60, as is the case when the door is above the plunger, in the second place the front edge of the door never has to bear the weight of the mass of coal in the tender, when such door is partially open, as is the case where the door is above the plunger, and in the third place, the door always forms a closure for the opening 24' when the apparatus is not in operation, which is not the case in the old arrangement with the door above the plunger, as in such old construction the door had to be moved from operative to closed position in order to close off the passage from the tender when the mechanism was not working. The use of a single discharge opening 24' and the single plate 25 with the plurality of openings, instead of a plurality of discharge openings and a plurality of plates is advantageous, as the tendency of the coal to bridge is eliminated, due to the fact that the area over which the bridge would have to extend is multiplied, and to the fact that the division member 55 between the openings moves and thus forms an unstable support for the coal.

It will be seen by reference to Fig. 2 that all the parts of the mechanism are operated directly from the cross-head 10, the framework 22 carrying auxiliary pistons 3 being directly connected thereto by means of the connecting rods 21, pistons 4, 5 and 6

being carried directly upon such cross-head, the plate 25 being directly connected with such cross-head by means of the connecting rods 27 and 28, and the central portion of 5 the cross-head being directly connected to the forwarding means in the chutes by means of the rod 52. The cross head is securely guided and maintained in position by the cylinders carrying the pistons 4, 5 and 6, 10 and it will be seen that the connections from the cross head to the parts operated thereby are so symmetrically arranged that there is no tendency to twist the cross head from the position shown. Power is also applied 15 to such cross-head directly by reason of the use of the two pistons 11 and 12 instead of the single cylinder heretofore used, and by reason of the location of the operating cranks 16 and 17 in corresponding positions 20 inside the outer pistons 4 and 6.

The operation may be briefly described as follows: Steam being applied to the engines 11 and 12, the cranks 14 and 15 are rocked, thus rocking the shaft 13 and the rocker 25 arms 16 and 17. The connections 18 and 19 between the rocker arms and the cross head 10 secure the actuation of such cross head and with it the main pistons 4, 5 and 6. The rocking of this cross-head similarly 30 rocks the frame 22 carrying the auxiliary pistons 3 by reason of the connections 20 and 21. This movement of the cross head 10 also secures the reciprocation of the plate or plunger 25 by reason of the connections 27, 26 and 28, as well as the oscillation of the bars 44 carrying the feed flaps 31 and the piston 32 by reason of the connections 50, 51 and 52. Charges of coal are thus fed intermittently and crushed by 40 the plate 25, such charges dropping into the hopper 58 in front of the pistons 32, and being forwarded step-by-step to the chutes 23 and 24 until the ends of such chutes are reached at which time it is discharged 45 through the passages 38 39 and 40 into the hoppers 33, 34 and 35 (Fig. 3), above the pistons 4, 5 and 6, which pistons feed the coal into the troughs 2 in the furnace. This fuel is fed through the troughs and agitated 50 therein by means of the plungers 3—3—3 acting in conjunction with the main plungers 4, 5 and 6 at the ends of the troughs. The engines 11 and 12 are preferably operated 55 upon one of the engines, so that a synchronous operation of the pistons is assured.

Having thus described my invention and illustrated its use, what I claim as new and desire to secure by Letters Patent is the 60 following:—

1. In combination in automatic stoker feed mechanism for locomotives, three feed cylinders for feeding fuel to the troughs of an underfeed stoker, a piston in each cylinder, a cross head mounted to reciprocate lon-

gitudinally of the cylinders and having connection with the pistons, and means for supplying fuel to the cylinders comprising a pair of feed chutes spaced apart and each having a passage leading to the central feed cylinder and a passage leading to an outside feed cylinder, and means in the chutes for forwarding the fuel. 70

2. In combination in automatic stoker feed mechanism for locomotives, three feed cylinders for feeding fuel to the troughs of an underfeed stoker, a piston in each cylinder, a cross head mounted to reciprocate longitudinally of the cylinders and having connection with the pistons, and means for supplying fuel to the cylinders comprising a pair of feed chutes spaced apart and each having a passage leading to the central feed cylinder and a passage leading to an outside feed cylinder, feeding means in the chutes, 75 and operating means therefor connected to the cross head and lying between the chutes. 80

3. In combination in automatic stoker feed mechanism for locomotives, three feed cylinders for feeding fuel to the troughs of an underfeed stoker, a piston in each cylinder, a cross head mounted to reciprocate longitudinally of the cylinders and having connection with the pistons, and means for supplying fuel to the cylinders comprising a pair of feed chutes spaced apart and each having its front end flared so as to discharge both to the middle cylinder and an outer cylinder, deflectors in front of the flared ends for guiding the fuel, and reciprocatory means in the chutes for forwarding the fuel. 95 100

4. In combination in automatic stoker feed mechanism for locomotives, three feed cylinders for feeding fuel to the troughs of an underfeed stoker, a piston in each cylinder, a cross head mounted to reciprocate longitudinally of the cylinders and having connection with the pistons, and means for supplying fuel to the cylinders comprising a pair of feed chutes spaced apart and each having a passage leading to the central feed cylinder and a passage leading to an outside feed cylinder, reciprocatory feed bars at the sides of the chutes, feed flaps carried thereby, a plate extending over the tops of both chutes and connected to the feed bars, and means for reciprocating the said plate, such means lying between the chutes and being connected to move with the cross head. 110 115 120

5. In combination in automatic stoker feed mechanism for locomotives, a plurality of feed cylinders on the locomotive for feeding fuel to the troughs of an underfeed stoker, a piston in each cylinder, a cross head for reciprocating the pistons, and means for supplying fuel to the cylinders comprising a pair of feed chutes spaced apart and each having a flared end adapted to feed to a plurality of feed cylinders, a 125 130

pair of discharge passages from the tender to the rear ends of the chutes, a single piston working through both passages, and connections for operating the said single piston with the cross-head.

6. In combination in automatic stoker feed mechanism for locomotives, a plurality of feed cylinders on the locomotive for feeding fuel to the troughs of an underfeed 10 stoker, a piston in each cylinder, a cross-head for reciprocating the pistons, and means for supplying fuel to the cylinders comprising a pair of feed chutes spaced apart and each having a flared end adapted 15 to feed to a plurality of feed cylinders, a discharge passage from the tender to the rear ends of the chutes, a single plunger working through the passage, a transverse bar pivoted intermediate its ends to the 20 rear end of the said single plunger, and a pair of substantially parallel connecting rods pivoted to the ends of said bar and to the cross-head.

7. In combination in apparatus for supplying coal to a locomotive fire-box, a tender provided with a gravity discharge passage, a chute and forwarding means beneath the tender whereby the fuel is forwarded to the fire-box, a piston working 30 transversely of the passage, a sliding door beneath the said piston, and means for operating the door.

8. In combination in apparatus for supplying coal to a locomotive fire-box, a tender 35 provided with a gravity discharge opening, a reciprocatory closure member therebeneath, a reciprocatory feed plate between said discharge opening and the closure member provided with an opening extending 40 through the plate and registering with the said discharge opening when the plate is in retracted position, and extending out past the closure member to permit the discharge of the fuel when the plate is in forward position, means for moving the closure member to regulate the discharge of fuel, and a chute and forwarding means beneath the closure member.

9. In combination in apparatus for supplying coal to a locomotive fire-box, a tender 50 provided with a gravity discharge opening, a closure member therebeneath, a reciprocatory feed plate between the said discharge opening and the closure member provided 55 with a plurality of openings spaced apart and extending through the plate, and all registering with the said discharge opening at the same time when the plate is in retracted position and extending out past the 60 closure member to permit the discharge of fuel when the plate is in forward position, means for reciprocating the plate, and a

chute with forwarding means beneath each opening in the plate in position to receive the fuel forwarded in the openings through 65 the plate.

10. In combination in apparatus for supplying coal to a locomotive fire-box, a tender provided with a single gravity discharge opening, a closure member therebeneath, a reciprocatory feed plate between the closure member and the discharge opening provided with a plurality of transverse receiving 70 means extending through the plate and all registering with the said opening when the plate is in retracted position and extending out past the closure member when the plate is in forward position, means for reciprocating the plate, and a plurality of chutes in 75 position to receive the fuel forwarded in the said receiving means, the discharge opening, receiving means and chutes being in substantial vertical alinement.

11. In combination in apparatus for supplying coal to a locomotive firebox, a tender 80 provided with a vertical gravity discharge passage, a piston working across such passage, a lateral discharge passage in alinement with the end of the piston and leading from the vertical passage, a sliding closure 85 plate lying beneath the vertical discharge passage and closing such passage when in retracted position, means for moving the closure plate forward from such retracted position to prevent a downward discharge 90 of the coal forced through the lateral discharge passage, and a forwarding means for receiving the coal located beneath the closure plate.

12. In combination in apparatus for supplying coal to a locomotive firebox, a tender 100 provided with a vertical gravity discharge passage, a piston working across such passage, a lateral discharge passage in alinement with the end of the piston and leading 105 from the vertical passage, a sliding closure plate lying beneath the vertical discharge passage and closing such passage when in retracted position, a support extending transversely beneath the front end of the closure plate, means for moving the closure plate forward from such retracted position 110 to prevent a downward discharge of the coal forced through the lateral discharge passage, and a forwarding means for receiving 115 the coal located beneath the closure plate.

In testimony whereof I have hereunto signed my name in the presence of the two subscribed witnesses.

CHARLES D. YOUNG.
